UNITED STATES PATENT OFFICE.

JOHN LIST, OF LAKE GEORGE, MICHIGAN.

SPACE-BAND CLEANER.

1,377,357.

Specification of Letters Patent. Patented May 10, 1921.

Application filed June 23, 1917. Serial No. 176,542.

To all whom it may concern:

Be it known that I, JOHN LIST, a citizen of the United States, residing at Lake George, county of Clare, State of Michigan, have invented a certain new and useful Improvement in Space-Band Cleaners, and declare the following to be a full, clear, and exact description of the same, such as will enable others skilled in the art to which it 10 pertains to make and use the same, reference being had to the accompanying drawings, which form a part of this specification.

This invention relates to space band cleaners and more particularly to an improvement on my former Patent No. 1,181,601, of May 2, 1916, and the object of the improvement is to provide an adjustable polishing roll that is yieldable in character. These and other objects and the several 20 novel features of the invention in its preferred form are hereinafter more fully described and claimed and shown in the accompanying drawings in which—

Figure 1 is a plan view showing my improved polishing roll.

Fig. 2 is a vertical section thereof.

Fig. 3 is an end view showing the means of pivoting the several sectors.

Fig. 4 is a transverse section of a space 30 band.

This invention is an improvement, as before mentioned, on my former Patent No. 1,181,601, entitled Space band cleaner, and in this invention the machine is practically 35 the same as in my former patent.

The polishing roll is made up of four sectors pivoted at 100 upon which they are adapted to swing. As shown more particularly in Fig. 2 these sectors are formed 40 with a rounded part 101 which conforms to the face 102 of the space band as shown in Fig. 4 and is adapted to polish the said face. As the polishing roll becomes worn the sectors thereof can be moved outwardly 45 by retracting the screws 103 slightly from the base part 104 of the polishing roll.

When the screws 103 are retracted as de-

scribed, the compressed springs 105 force the sectors of the polishing roll outwardly on the pivot 100 until the said sectors engage the heads of the screws 103. Thus when the polishing roll becomes worn it may be adjusted to assume the correct position in relation to the companion polishing roll for polishing the space bands. 50 55

As in my said former patent, one of the rolls should be yieldably mounted after the manner disclosed in the said patent. This roll is the roll provided with the hinged segments and permits an adjustment of the 60 diameter of the roll as will be readily understood. By the means described it is evident that the roll may be adjusted in diameter to take up wear and thus a device is secured that is of long life and, while of very simple nature, is efficient in operation. 65

Having thus briefly described my invention, its utility and mode of operation, what I claim and desire to secure by Letters Patent of the United States is—

1. In a space band polishing device, a polishing roll formed of several segments pivoted to the base of the roll and means for changing the diameter of the roll consisting of springs adapted to force the segments 75 outwardly on their pivots and adjusting screws adapted to limit movement of the said segments.

2. In a space band polishing device, a substantially cylindrical polishing roll formed 80 of a plurality of segments with similar outer curved surfaces of a shape to practically conform to the surface of the space band to be cleaned, a hub member on which one end of each of the segments is pivoted, 85 a spring for each segment carried by the hub member tending to force the segments outwardly to increase the diameter of the roll, and adjustable means for each segment limiting the extent of movement thereof by 90 each spring.

In testimony whereof I sign this specification.

JOHN LIST.
